UNITED STATES PATENT OFFICE

CHARLES E. OLSON, OF BRIDGEPORT, CONNECTICUT

APPARATUS FOR RESCUING CREWS OF SUBMARINES

Application filed July 23, 1928. Serial No. 294,655.

The object of this invention is to provide rescue apparatus which includes a special section to be connected to one of the hatch-ways in the hull of a sunken vessel, this connection to be secured to other sections constituting a tube designed to extend slightly above the surface of the water and downwardly to the vessel, and a vertically movable element or lifting device operating within 5 the tube for receiving and lifting to the surface the members of the imprisoned crew.

A further object is to provide for the use of the divers, a pontoon having the necessary air and water connections determining position below the surface, and permitting of the assembly of sections of the apparatus, at any reasonable depth, to prevent interference with the operations by rolling seas.

With the foregoing and other objects in view, the invention consists in the novel construction and arrangement of elements described, illustrated and claimed, it being understood that modifications may be made within the scope of the claim without departing from the spirit of the invention.

In the drawings forming part of this application:—

Figure 1 is a plan view showing a portion of the hull of a vessel, with a hatch secured to one of the hatch-ways or man-holes.

Figure 2 is a section on line 2—2 of Figure 1 and shows the securing means for the outer cover of the hatch-way, and means for releasing the inner hatch or man-hole cover.

Figure 3 is a bottom plan view of the structure of Figure 2.

Figure 4 is a vertical section thru the lower section of the apparatus to be secured to the edge portions of the hatch-way of Figures 1 and 2.

Figure 5 is a section on line 5—5 of Figure 4, and shows a portion of the wall of the lower tube section, and the vertical rails for guiding the elevating device.

Figure 6 is a vertical section thru a pontoon with means for admitting water for submerging purposes, and, at the right, means for admitting air for ejecting water, thru the check valve at the left, when the pontoon is to be raised.

Figure 7 is a vertical section of the upper portion of the tubular structure within which the elevator operates, the upper tube connection being used for admitting air and forcing the water out of the tube.

Figure 8 is a vertical section thru a portion of the tubular structure, the elevating device for individual members of the crew therein being in elevation.

The lower section of the apparatus forming the subject matter of this case is shown especially in Figure 4 and includes an upper wall 10, side portions, and a lower portion 11 having a hatch-way or man-hole 12, the edge portions of which are in the form of flanges 13 as shown at 13. The flange or flanges are to be secured within a depressed portion or recess 14 in the hull 15 of the sunken vessel. This depressed portion 14 is closed by an outer man-hole cover or hatch 16.

An inner hatch or man-hole cover 17 includes a lower flanged portion 18 and an outer threaded portion 19 for cooperation with internal threads on the flange 15' of the hull plate 15.

Retained by flange 18 of the inner man-hole cover is a split ring or the like 20 secured by elements 21 and carried by an arm 22 having formed therewith a tubular portion 23. The latter comprises a part of a link hinge 25 pivotally mounted at 26 on a bracket 27 secured to the under side of the hull plate adjacent to the hatch-way under discussion. This form of mounting permits of the movement of the hatch 17 from the position of Figure 2 to that of Figure 4.

The hatch 17 includes a flanged portion 30 formed as a worm wheel for cooperation with worm 31 on shaft 32. This shaft carries a worm wheel 33 engaged by worm 34 on shaft 35. The shaft last named may be rotated by means of a crank, not shown, which may be applied to the inner end, at 35' or to the outer end portion 35'', after the removal of the cap nut or plug 36. Within the housing or lower section which may be considered as a whole as section 38 of the tubular structure, is a bracing device 39, and rails 40 and 41 are secured respectively to this element 39 and to the portion or bracket element 39'. 95 100

The upper wall 10 of the section 38 carries a flanged portion 42 to which the next tubular section 43 is to be secured by means of bolts 44, a gasket being shown at 45. The rails 40 and 41 are retained in section 43 by securing devices 46 of any suitable character. Completing the section 38 are other man-hole or hatch-way connections 46 and 47, these members of the lower hatch-way connection being at various angles, to permit the lower section 38 of the tubular structure to be secured as nearly as possible in a vertical position, notwithstanding the position in which the hull of the vessel may be lying.

It should be added that the lower section 38 carries a heavy ring bolt 48 for a cable 49 by means of which the section may be raised, and lowered. A valved connection 50 permits of the ejection of water, under air pressure from above, thru the vertical tube, after connection has been effected between the flanges 13 and the hull plate of the vessel.

The upper section of the tubular structure is shown in Figure 7 and is designated 55, the rails being indicated by 40 and 41 as before. This section 55 is closed by cap plate or cover plate 56 retained by bolts 57. Air tube 58 is connected with plate 56 and communicates with the interior of the tubular structure for the purpose of introducing air under pressure and forcing out the water, as indicated. After the water has been thus ejected, the elevator or cage 60 is to be lowered into the tubular structure, and is provided 35 with a door-way 61, the rollers or wheels 62 cooperating with the rails 40 and 41 in an obvious manner.

The lower section of the tubular structure is to be secured by divers, and the hatch plates 16 and 17 are to be released, after the water has been driven out of the tube structure, and the valve 56 closed. It is assumed that a man will be sent down with the elevator or cage 60 and will render any assistance necessary to the members of the crew 45 who are to be rescued from the sunken vessel.

In the event that any are unconscious they may be removed by use of harness or the like by which they are to be lifted into the elevating device and thence carried on to the surface. It is of course understood that the upper section 55 of the tubular structure is to project above the surface of the water, a sufficient distance to permit the device 60 to be raised so that the door-way 61 will be opposite a corresponding door-way in the upper tube section 55.

In order to afford protection from rolling seas and permit the divers to operate 60 successfully, and to carry to the scene of operations all sections of the apparatus required,—a somewhat large pontoon will be employed, equipped as in Figure 6. This structure is represented as a whole by reference number 70, and the upper portion car-

ries an eye bolt 71, and the lower portion an eye bolt 72, these elements being designed for connection with cables such as 73 and 74. The pontoon is to be used for raising and lowering the main sections of the apparatus.

An air hose 75 extends to the air inlet connection 76 for the pontoon, this connection being under the control of a valve 77, which may be operated by chain 78. The valve is held closed by a spring 79, and is opened by producing tension on chain 78, so that the divers may introduce compressed air for ejecting water from the interior of the closed pontoon, thru connection 80 controlled by a check valve 81.

Water may be admitted to the pontoon 70 thru connection 82 controlled by valve 83, the latter including an arm 84 connected with a chain 85, which may also be operated from any convenient point by one of the divers, for admitting water, to the required degree to permit of submerging the pontoon, in the manner desired,—the admission of water and the admission of air for ejecting the water, determining the degree of submergence.

What is claimed is:—

In an apparatus of the class described, a lower tube section and housing having man-holes in a plurality of walls extending at an angle with each other, additional tube sections connected with that first named, car guiding rails extending thru said sections, a structure having a hatch-way for connection with one of the man-holes of the housing, means for closing the hatchway, and rotatable means for releasing the closing means from the interior and exterior of the structure, the rotatable means including intermeshing elements one of which is tiltable incident to the closing movement, and a prerequisite thereof.

In testimony whereof I affix my signature.

CHARLES E. OLSON.
